UNITED STATES PATENT OFFICE.

HERMAN A. POPPENHUSEN, OF HAMMOND, INDIANA, ASSIGNOR TO GREEN ENGINEERING COMPANY, OF EAST CHICAGO, INDIANA, A CORPORATION OF ILLINOIS.

FURNACE.

Application filed August 7, 1922. Serial No. 579,987.

This invention relates to furnaces equipped with mechanical stokers in the form of progressive feed grates.

One object of my invention is to provide an effective combination of water cooled conduits at the sides of the grate, water back pipes adjacent the rear of the grate, and an adjustable fuel retarder in the space between said grate and said water back pipes, this being accomplished by spacing said pipes high enough above the grate to allow the conduits to pass thereunder and having the ends of the retarder terminate short of said conduits.

Another object of my invention is to provide a novel air seal for the spaces between the water back pipes, bridge wall overhang and the adjustable retarder and one that will be effective in all positions of adjustment of the retarder and permit adjustment of the latter without breaking said seal.

The invention consists in the matters hereinafter described and more particularly set forth in the annexed claims.

In the accompanying drawings—

Fig. 1 is a longitudinal vertical sectional view taken through a furnace embodying the features of my invention;

Fig. 2 is a similar view on a large scale of the structure adjacent the rear discharge end of the grate;

Fig. 3 is a transverse vertical sectional view taken on line 3—3 of Fig. 2;

Fig. 4 is a rear view of the furnace and showing the mechanism there, provided for adjusting the fuel retarder toward and from the grate; and

Fig. 5 is a perspective view of one end of the fuel retarder.

The furnace structure shown in Fig. 1, includes a mechanical stoker in the form of an endless chain grate 1 which extends through the front wall 2 of the furnace setting toward the bridge wall 3 thereof.

The rear or discharge end of the grate 1 terminates short of said bridge wall 3 to provide a vertical passage for the ash discharge over the rear end of said grate.

Extending along the sides of the grate 1 are pipes or conduits 4, 4, these are arranged in pairs at each side of the upper lead 5 of the grate, as illustrated in Fig. 3 and are supported by the adjacent side walls 6, 6 of the furnace setting, as shown in said fig-

ure. The arrangement of these pipes or conduits 4, 4 is such that they are in direct contact with the fuel bed carried by the upper or top lead 5 of said grate throughout substantially the entire length thereof, as shown in Fig. 1. Said pipes 4, 4 constitute the contact surfaces between the fuel bed on the grate and the side walls 6, 6, and being water cooled prevent the incandescent fuel adhering to the side walls 6, 6 to damage them and form clinkers at the sides of the grate to impede the movement of the fuel bed.

In the arrangement shown, said conduits 4, 4 are water cooled by being included in the boiler circulation. This is accomplished by having water boxes 7, 8 at the ends of each set of conduits 4 and connecting these boxes by pipes 9, 9 with the front and rear headers 10, 11, respectively, of the water containing elements of the boiler. The box 7 is at the inlet ends of its set of conduits 4, 4, while the box 8 is at outlet ends thereof. To facilitate the flow of steam bubbles occurring in the conduits 4, 4, they are inclined upwardly from the rear, as indicated in Fig. 1.

The bridge wall 3 has an overhang 12 extending over the rear or discharge end of the grate 1 above the same, as shown in Figs. 1 and 2. Arranged in this space are water back pipes 13, 14. Said pipes 13, 14 are vertically spaced apart and extend horizontally between the side walls 6, 6 of the furnace setting, as shown in Fig. 3. The ends of said pipes 13, 14 extend into said walls 6, 6 and are connected together at one end by a U or like fitting 15. The opposite ends of said pipes are connected with the headers 10 and 11, respectively, by pipes 16, 17 to place said pipes 13, 14 in boiler circulation, and maintain them relatively cool.

Each set of side conduits 4, 4 pass under the water back pipes 13, 14 adjacent the side walls 6, 6 of the furnace setting and continue on beyond the rear or tail end of the grate 1 through the bridge wall 3, as shown. To secure effective results, these conduits 4, 4 must extend substantially the full length of the grate in order to provide water cooled surfaces for the sides of the fire. This requires that the side pipes 4, 4 be at the rear end of the grate and to accomplish that they must extend under the

water back pipes 13, 14. The result is that ² nects the retarder to the water service supply. said water back pipes, to allow the side pipes 4, 4 to pass under them without bend, must be spaced or raised above the upper lead 5 of the grate a distance suitable for that purpose. As shown in the drawings, this is fulfilled by having both of the water back pipes 13, 14 above the uppermost of the side conduits 4, 4. The latter also need to extend rearwardly beyond the tail end of the grate 1 to have their rear ends accessible for connection with the rear header or other source of cooling water supply.

The space made necessary between the lowermost water back pipe 14 and the upper grate lead 5 to allow the side conduits 4, 4 to pass beneath the water back pipes, is of such height that the furnace could not be effectually operated without a fuel retarder in said space.

The fuel retarder which I have provided for this space comprises a pipe or conduit 18 extending transversely across the grate lead 5 substantially parallel with the water back pipes 13, 14 and below the same. The side pipes 4, 4 extending under the water back pipes 13, 14 makes it necessary to terminate the ends of the retarder pipe 18 short of the side pipes 4, 4 in order not to interfere with them and allow for vertical adjustment of said retarder pipe.

To maintain a circulation of cooling water through said retarder pipe 18 and also to provide for vertical adjustment of the same for regulating and controlling the discharge over the rear end of the grate 1, I provide the following construction.

Secured to each end of the retarder pipe 18 is a casting 19. These castings close the ends of said pipe, and each has two holes 20, 21 made in it, as shown in Fig. 5. These holes permit connections to be made with the ends of the pipe 18 for circulating cooling water through. When the connections are made the upper hole at one end of the pipe constitutes the inlet and the lower hole at the opposite end of the pipe is the outlet. The remaining two holes not used, one at each end of the pipe, are closed by plugs 23, as indicated in Fig. 2. By having two holes in each casting 19 no attention need be paid to which ends of the pipe the castings are applied, as there is always an upper and a lower hole for the inlet and outlet, respectively. This, therefore, facilitates connecting up the retarder pipe 18 with the water supply when setting up the furnace as well as when on a repair job. Pipes 24, 25 are connected with the inlet and outlet holes at the ends of the retarder pipe 18, and have swing joints in their connections with the main inlet and outlet pipes in one of the side walls 6, as shown in Fig. 2. This allows the pipes to move as the retarder pipe 18 is given vertical adjustment, and con-

Each casting 19 has a rearwardly extending web 26. These webs are secured to arms 27, 27 rockably mounted in brackets 28 fixed to the bridge wall 3, as shown. These brackets are below the grate 1 and the arms 27, 27 extend upward and forward for connection with the webs 26, 26. The arms 27, 27 rockably or pivotally mounted on the bridge wall 3 enables the retarder 18 to be moved or adjusted to and from the grate surface 5, and resists the end thrust of the fuel bed thereon.

To move the arms, I provide at the rear of the bridge wall 3, a horizontal shaft 29. This is arranged above the grate 1, and is journaled in brackets 30, 30 on said wall. Fixed on said shaft 29 are two rack pinions 31, 31 one for each arm 27 and in alignment therewith. For each arm 27 is a rack bar 32 in mesh with the pinion for said arm. These bars extend through enlarged openings or channels 33 in the bridge wall 3 and are pivoted to the respective arms 27, as shown.

The brackets 30 have side plates and the pinions 31 and bars 32 are arranged between with the bars resting on the pinions. To hold the bars in mesh, each has a pin 34 with its ends in inclined slots 35 in the side plates of the associated brackets. These pins 34 also indicate by their positions in the slots 35 the extent to which the retarder 18 has been adjusted above the upper grate lead 5.

For rotating the shaft 29 and thus adjusting the retarder 18, there is a worm wheel 36 fixed in said shaft. This wheel is in mesh with a worm 37 on a short shaft 38 journaled in a bracket 39 on said bridge wall 3. The shaft 38 has a hand wheel 40 at its outer end for turning it.

Arranged to the rear of the water back pipes 13, 14 is a shield 41. This is a metal plate extending between the side walls 6, 6 and closing the space between the overhang 12 and the uppermost water back pipe 13 to the passage of cold air into the combustion chamber from over the rear end of the grate. This plate extends downward to the lower pipe 14 and closes the space between the two pipes and also forms a backing for the fire clay or other heat resistant material 42 packed in said space.

To close the space between the retarder 18 and the lower water back pipe 14 in all positions of vertical adjustment of the latter, I provide an upright member or flange 43 on the retarder pipe 18, as shown. This flange extends upward and rearward to clear the lower water back pipe 14 and contacts at its upper end at all times with a plate 44 extending downward from the shield 41 and hinged or pivoted thereto, as shown.

As the retarder 18 is raised and lowered, the plate 44 moves with it and being in contact with the flange 43 seals the space between said plate to passage of cold air into 5 the combustion chamber from the rear of the grate.

The structure shown and described provides an effective and efficient combination of side conduits, water back pipes, and adjustable fuel retarder, all water cooled to prevent the adherence of the fuel bed thereto and arranged and constructed in a manner giving the best furnace efficiency. These parts are furthermore so associated that the 10 arrangement of one is such that it accommodates and co-acts to the best results with the others.

While I have shown and described herein in detail a structure embodying the features 20 of my invention, it is of course to be understood that the details of construction may be variously arranged and modified without departing from the spirit and scope of my invention.

25 I claim as my invention:—

1. The combination in a furnace, of a traveling grate discharging at its rear end, a water back pipe spaced above the grate and extending across the same adjacent its 30 rear end, fluid cooled conduits extending along the sides of the grate and arranged to be in direct contact with the fuel bed thereon, said conduits extending under said pipe, and a fuel retarder vertically adjustable in 35 the space between said grate and pipe and having its ends terminating short of said side conduits.

2. The combination in a furnace, of a traveling grate discharging at its rear end, a water back pipe spaced above the grate and extending across the same adjacent its rear 40 end, fluid cooled conduits extending along the sides of the grate and arranged to be in direct contact with the fuel bed thereon, said conduits extending under said pipe, a fuel retarder extending across the grate between 45 said grate and pipe and having its ends terminating short of said side conduits, and means mounted on the furnace setting for supporting said retarder for vertical 50 adjustment and for resisting the end thrust of the fuel bed thereon.

3. The combination in a furnace, of a traveling grate discharging at its rear end, a water back pipe spaced above the grate and extending across the same adjacent its rear end, fluid cooled conduits extending along the sides of the grate and arranged to be in direct contact with the fuel bed thereon, said conduits extending under said pipe, and a vertically adjustable water cooled fuel 60 retarder extending across the grate in the space between said grate and pipe and having its ends terminating short of said side 65 conduits, the latter and pipe being in boiler

circulation and the retarder in the service supply without slotting the side walls of the furnace setting.

4. The combination in a furnace having 70 side walls, of a progressive feed grate therebetween, a fuel retarder having its ends terminating short of said side walls, curved arms to the rear of said retarder and having their upper ends connected therewith, said arms at their lower ends having pivotal 75 connection with the furnace setting to the rear of said grate, rock bars pivoted to said arms and extending rearwardly therefrom, a shaft supported by said furnace setting to the rear of said arms and provided with pinions in mesh with said rock bars, and means for turning said shaft for adjusting the retarder toward and from said grate.

5. The combination in a furnace having 80 side walls and a bridge wall of a progressive feed grate between said walls and having its rear end terminating short of said bridge wall, a fuel retarder extending across the grate adjacent its rear end, said retarder having its ends terminating short of said 85 side walls, curved arms in the space between the rear end of the grate and said bridge wall, said arms having their upper ends connected to said retarder and their lower ends pivoted to said bridge wall below said grate, 90 rack bars extending through said bridge wall in said openings and connected with said arms, a shaft supported by said bridge wall and provided with pinions in mesh with said 95 rack bars, and means for turning said shaft. 100

6. The combination in a furnace having 105 side walls and a bridge wall with an overhang, of a traveling grate between said side walls with its rear end terminating short of said bridge wall under said overhang, vertically spaced water back pipes beneath said overhang and extending across the grate adjacent its rear end, a vertically adjustable fuel retarder extending across the grate in the space between the same and the lowermost pipe and having its ends terminating short of said side walls, a plate to the rear of said pipes and arranged to close the spaces between the same and said overhang, a second plate hinged to the first plate and extending downward to the rear of the lowermost pipe, and an upwardly projecting plate on said retarder and engaging said second plate to keep closed the space between the lowermost pipe and said retarder in all positions of adjustment thereof. 110

7. The combination in a furnace having 115 side walls, of a progressive feed grate therebetween, a vertically adjustable fuel retarder extending across said grate adjacent its discharge end, said retarder having its ends terminating short of said side walls, said retarder being in the form of a conduit, castings at the ends of said conduit to close the same, said castings having rearwardly ex- 120 125 130

4
tending webs inside of said walls, water pipes within said walls and connected with said castings for circulating cooling water through said retarder, curved arms to the 5 rear of said retarder and connected with said webs at one end, the other ends of said arms being pivoted to the furnace setting

at the rear of said grate, and means for adjusting said retarder toward and from the 10 grate by moving said arms.

In testimony that I claim the foregoing as my invention, I affix my signature this 1st day of August, A. D. 1922.

HERMAN A. POPPENHUSEN.
